UNITED STATES PATENT OFFICE

1,971,647

CUT-OUT MACHINE

Benjamin W. Freeman, Cincinnati, Ohio

Application May 19, 1932, Serial No. 612,365

49 Claims. (Cl. 164—93)

The present invention relates to shoe machinery and more particularly to a type of machine adapted to form cutouts, perforations and the like upon skins, upper blanks, and fitted 5 and closed shoe uppers and various portions of a shoe.

Among the objects of the invention is the formation of ornamental designs on and in the work by the production of ornamental cutouts in 10 the work.

Operating difficulties and problems arise when a piece of work, formed with portions of varying thickness is ornamented, that are not found when flat work of uniform thickness is treated, and an 15 important feature, and object of the present invention resides in the construction of a die unit, in which part of the cutting members are resiliently mounted and movable relative to the die block or base, and others of the cutting members are fixed to the base, for the purpose of 20 handling work of non-uniform thickness, and facilitating application of an ornamental cutout design to both the thick and thin portions of the work.

25 It is essential that the work be accurately aligned with the die unit, prior to the actual cutting of the work, and another object resides in the provision of a resilient mounting or die holder for supporting the die unit in position in the machine, making it possible to lower the die toward 30 the work by providing for slight relative movement between the die holder and that part of the machine to which it is attached.

In a preferred embodiment, the device is illustrated as mounted upon a movable plunger which reciprocates toward and from a fixed work support, but it is obvious that the invention is 35 equally adaptable to a machine in which the work support moves to the die, as described in my co-pending application, Serial No. 587,431, filed January 18th, 1932.

Heretofore when using a cutout machine with a fixed anvil support, difficulties have been encountered, with certain types of shoes, because 45 of the way designs may be located on the shoes, or due to the manner in which the uppers are fitted. Because of the manner in which certain shoe uppers are fitted, necessitating the placing of the work on the anvil, in a prescribed position 50 with relation to the die attached to the head, or die supporting mechanism, it is frequently difficult to readily and easily place the work, if not impossible, particularly on small sized uppers to proper location and to position these uppers 55 without changing the fitting or releasing portions

of the lining or otherwise changing the method of making the shoe upper. It has accordingly been customary where such changes were impractical, to make an extra set of dies and it is still difficult even though changes are made, to 60 perform the cutting out operation with speed. All of these difficulties are mainly to the fact that these machines have no capacity for changing the relative position of the anvil with respect to the die.

Accordingly, in order to overcome the aforesaid difficulties, it is an object of the present invention to provide an adjustable, anvil supporting mechanism.

To the attainment of the above and other objects which will appear as the description proceeds, reference may be made to the accompanying drawings, in which:

Fig. 1 is a partial front elevation of the machine;

Fig. 2 is a partial side elevation of the machine;

Fig. 3 is a perspective of the die unit;

Fig. 4 is a section of the die;

Fig. 5 is an elevation of the die in one operating position, illustrating a section of the work;

Fig. 6 is an elevation of the die in a subsequent operating position;

Fig. 7 is a partial plan view of the work showing its condition when the die is in the position of Fig. 5;

Fig. 8 is a partial plan of the work after the operation of Fig. 6;

Fig. 9 is a section of the resilient die holder;

Fig. 10 is a bottom plan of the die holder; and

Fig. 11 is a top plan of the die holder.

The present machine is adapted for use in cutting blanks from a skin, in ornamenting, cutting or perforating flat and other work such as upper blanks, closed or fitted uppers, etc. It comprises generally a power driven plunger cooperating with the die (in the illustrated embodiment the die is mounted on the plunger for movement therewith, although it might be readily mounted independently of the plunger) and an anvil or work support upon which the work is positioned, this work support being shaped to provide clearance at its sides whereby a fitted upper may be readily positioned thereon without buckling that part of the upper to be cut. A suitable backing medium of paper or its equivalent is usually provided between the work and the anvil, and the anvil itself may be surfaced with material softer than the cutting edges of the die. Means are provided for properly aligning, gauging and

65

75

80

85

90

95

100

105

110

positioning the work, and for holding same in proper position with respect to the die.

Referring more specifically to the drawings, in which like reference numerals designate like parts, it will be observed that the machine comprises generally a base portion 10 having an upwardly extending frame or casing portion 11 which terminates in a head portion 12, such head portion overhanging the front part of the base 10 to provide an enclosure within which is positioned an adjustably mounted, anvil 13, as hereinafter described. Mounted for vertical reciprocating movement within the head 12 is a plunger 14 carrying a cutting die unit 15, which latter is aligned 15 with the anvil 13. A constantly driven pulley 16, connected to any convenient source of power, serves as a mode of operating the plunger, there being a single revolution clutch indicated generally at 17 effective to connect the pulley to the 20 mechanism for reciprocating the plunger. A clutch control mechanism 18 (Fig. 2) is provided and a treadle rod 19 connected to a pivotally mounted lever 20 is effective to initiate actuation of the control mechanism and clutch when the 25 treadle rod 19 is depressed. When the clutch, through depression of the treadle rod connects the pulley 16 to the plunger actuating mechanism, for a single revolution of the pulley there will be effected a single complete reciprocation 30 of the plunger 14 and die 15 toward and from the work. A safety latching mechanism 21 and 22, hereinafter described, and forming a part of the clutch control mechanism 18 is provided to prevent actuation of the clutch and plunger 14 at 35 other than the proper time in the cycle of operations.

In Figs. 5 to 8 there is illustrated a fragmentary laminated quarter of a shoe formed of a lining L, the quarter material M and an overlay or 40 applique A.

Fig. 7 shows the quarter prior to an ornamenting operation thereon, and Fig. 8 shows the same work after it has been ornamented by perforating at 23, 24 and 25. In operating on this type of shoe, it will be noted that part of the design is 45 cut through the applique or strap portion, and the remaining ornamentation applied to the quarter proper. In attempting to ornament shoe parts of this nature, a condition arises, which is 50 very troublesome to shoe manufacturers, caused by the fact that the thickness of the applique causes the cutting edges of a die, as ordinarily constructed, to strike the applique first and prevents other cutting edges of the die from reaching 55 the thinner portions of the upper. In aligning the work with respect to the die, it is desirable to utilize the edge of the applique as an abutment against which the cutting edges of the die may be placed prior to the cutting out operation, but 60 with conventional dies, it is practically impossible to position the die against the work in such a manner that certain cutting edges of the die will engage the abutment formed by the edge of the applique. This same condition prevails in machines where the die is stationary and work is moved to the die.

In order to make it possible to either lower the die or raise the work, so that those cutters which are to operate in the lesser thicknesses of 70 the material, can contact with the upper, while other cutters which are to operate in thicker parts of the work can also contact with the work, there is provided a resilient mounting for a part of the cutters such that in the preliminary engagement of the cutting edges of the die with

the work, for aligning purposes, those cutters which operate on thinner portions of the work will have a yieldable, advanced position over the balance of the cutters.

To this end, the die unit 15 (Figs. 3 and 4) is formed with a die block 26 to which is secured an extension 27 carrying the cutter 28. Also carried by the block is a series of struts or sleeves 29 within which are mounted for sliding movement, studs 30 normally spring pressed outwardly. A composite plate 31 is connected to the studs for movement relative to the sleeves 29 and block 26, and carries the cutter 32, and perforating tubes 33. Pins 34 serve to limit movement of the block 31 in either direction.

Interiorly of the extension 27, from the cutter 28 to the open interior of the unit, is a conduit 35 for the passage of chips, and all of the cutters 28, 32 and 33 are hollow for this purpose. The cutters are spaced from the base by the struts or sleeves 29 and form in conjunction with the sleeves and base, a chip receiving chamber, as will be evident from Fig. 4.

When the cutting out operation takes place, the cutter 28 first passes through the applique 100 A and as it reaches the quarter M it is then in the same plane with the cutter 32 and perforating tubes 33, which are now solidly in contact with the die block 26. In this position the entire die passes through the quarter M and lining L and into the paper, brass plate or other backing material generally used between the work and the support.

It will be noted that the cutter 28 is positioned so that it will not interfere with the vision of the operator, whereby the operator may locate the resiliently mounted cutters 32 and 33 with a side of cutter 32 against the edge of the applique.

The resiliently mounted die, not only handles this type of work satisfactorily, but is equally effective with work having a single uniform thickness throughout.

While in the present embodiment the die is mounted upon a movable plunger and adapted to pierce a fixed work piece from above, it of course is entirely practical to reverse the operation and hold the die block against movement while making the work support movable toward and from the die. In fact the die may be located below the work and pressure applied either from above the work by moving the plunger down against the work and die, or by moving the die and work up to a resistant surface. As an illustration of such reversal of operation reference may be made to my copending application Serial No. 587,431 above noted.

The die is connected to the plunger by a die holder 36 attached to the plunger 14 by means of a dovetail strip 37, slideable in a mating groove on the face of the plunger, and detachably secured therein, in a manner similar to that used in the above mentioned application.

Extending upwardly from the holder at either side thereof are sleeves 41, into which sleeves extend studs 42, attached at their lower ends to the holder 36.

The holder is formed of a pair of separable plates 43 and 44, the dove-tail strip 37 being connected to plate 43 and the plate 44 being provided with a thickened portion 45 to accommodate an attaching member 50 engageable with the die block. The sleeves 41 are connected to the plate 43 and the studs 42 are connected to the plate 44. Projections or extensions 46 of the studs 42 are arranged on the lower face of 150

the plate 44 and shaped to receive levers 47 which are keyed to a shaft 68 extending transversely across the machine. A lever 39 mounted on one end of the shaft and connected to a treadle rod 40 is effective to actuate the arms or levers 47 which engage the die holder. The die block 15 is provided with a projection 38 and the holder is provided with an opening 51 to receive the projection. The projection is slotted at one side and the lever or attaching member 50 extending through the thicker portion of the die holder and normally blocking the opening 51, is partially cut away at 53. A spring 52 acts to hold the lever 50 in the position indicated in Fig. 9. When the lever is turned to bring the cut away portion thereof in registration with the opening 51, the projection 38 may be inserted. When the lever is released the spring will then return it to its original position and it will then engage the slotted part of the projection, thus forming a means of attachment between the die block and die holder. Suitable attaching means having a handle 54 serve to secure the die holder to the plunger. The die block 26 is perforated as indicated at 55 and the holder 36 carries a pin 56 adapted to enter the perforation. The purpose of the pin and perforation is to insure accurate positioning of the die and die block in the holder, and also to prevent twisting or slipping of the die block about the projection 38.

It will be apparent that movement of the treadle rod 40 and lever 39 will move the plate 44 relative to the plate 43 which is secured to the plunger 14, through movement of the arms 47, and in turn the die 15 will move relative to the plunger upon which the die holder is supported. Depression of the treadle rod moves the die downwardly and spring 48 encircling the sleeve 41 and stud 42 will be effective to return the die to its original position against the holder upon release of the treadle. The springs are kept in position by washers 49 on the end of the stud remote from the projections 46. In other words, while the die 15 is mounted on the plunger for movement therewith and in effect is rigid therewith during a cutting operation, nevertheless it is not fixedly mounted and can be moved relative to the plunger.

Having thus described my invention the operation thereof will be readily apparent. The die holder is attached to the plunger of the machine by means of the dove-tail 37 and the die block attached to the holder by means of the projection 38 and lever 50. A piece of work is positioned on the anvil, and the die lowered from the plunger by means of the treadle 40 which causes a separation of the plates 43 and 44. With the die in this lowered position the work may be accurately aligned by reference to the abutment formed by the edge of applique A.

The lever 22 which is keyed to the shaft 68, for movement with the arms 47 is operatively connected to a latch member 21 arranged to slide transversely of the mechanism 18, and is effective when moved to the left from the position shown in Fig. 2 to release the mechanism 18 whereby the clutch may be actuated by treading of the levers 19 and 20. When in reverse position the latch 21 locks the mechanism 18 against any inadvertent treading by the lever 19.

It will be seen that the clutch is locked at all times that the die 15 is spaced a substantial distance from the work, as the latch will not release the mechanism 18 until the die has reached

a predetermined position relative to the work. When the die reaches such position, usually sufficiently close to permit aligning of the work, there will be a space between the plate 43 attached to the plunger 36, and the plate 44 to which the die is attached. Depression of the lever 20 will clutch the machine and cause the plunger to drive the plate 43 against the plate 44, thus effecting a cutting out of the work. After the machine has been clutched the treadle 40 may be released and the springs 48 will force the plate 44 upward withdrawing the die from the work.

The plunger is now in raised position and the die will also have raised upon release of treadle connection 21, and as the clutch is of the single revolution type further reciprocation of the plunger and die will cease until the machine is again treadled.

The details of the clutch 17 and clutch control mechanism 18 including this latching mechanism form no part specifically of the present invention, and for a more complete description thereof reference may be made to my copending application Serial No. 515,346, filed February 12th, 1931, which although directed to a different machine from that described herein, utilizes a clutch and control mechanism which may be satisfactorily used with either machine.

In order to overcome various difficulties in placing the work on the anvil in a predetermined position with respect to the die and die holding mechanism, it is found desirable to provide an adjusting mechanism for supporting the anvil 13, whereupon the anvil may be moved with relation to the die mechanism. Referring particularly to Figs. 1 and 2 it will be observed that the anvil 13 is mounted in a block 55, which block 55 is in turn mounted for sliding movement in a guide 56 in the base portion 10 of the frame 11. Movement of the block 55 is effected by a hand wheel 57, operating on a stud 58, which stud is pinned to the block 55 so that the turning of the hand wheel moves the block and stud either in or out depending on the direction of rotation of the hand wheel. The wheel 57 is held against the face of the guide 56 by means of a plate 59, the plate being affixed to the front of the base portion 10 over the guide and so made that the shouldered shank on the hand wheel rides between this plate and the portion 10.

Having thus described my invention, what I claim as new and desire to secure by Letters Patent of the United States, is:

1. A machine for ornamenting shoe parts comprising a work support, a die unit including a die carrier and a die mounted on said carrier, means to move said die relative to its carrier, and through a plane normal to the work support whereby work thereon may be aligned relative to said die, and means to provide relative movement between said work support and die unit through a plane perpendicular to the work support, thereby to ornament the work.

2. A machine for ornamenting shoe parts comprising a work support, a die unit including a die carrier and a die, means resiliently attaching said die to the carrier, means including said resilient means to move said die yieldingly relative to its carrier and in proximity to the work support whereby work thereon may be aligned relative to said die, and means to provide relative movement between said work support and die unit through a plane perpendicular to the work support, thereby to ornament the work.

3. A machine for ornamenting shoe parts comprising a work support, a member movable toward and from said work support, a die carried by said movable member for movement therewith, means to move said die relative to said member and through a plane normal to said support whereby the work may be aligned on said support relative to said die, and means to actuate said member and die as a unit, through a plane perpendicular to the work support, thereby to ornament the work. 80
4. A machine for ornamenting shoe parts comprising a work support, a member movable toward and from said work support, a die, resilient means to attach said die to said member for movement therewith, means including said resilient mounting to move said die yieldingly relative to said member and toward said support whereby the work may be aligned on said support relative to said die, and means to actuate said member and die as a unit, through a plane perpendicular to the work support, thereby to ornament the work. 90
5. A machine for ornamenting shoe parts comprising a work support, a die unit including a die carrier and a die attached to said carrier, means to move said die relative to its carrier and in proximity to the work support, whereby work thereon may be aligned relative to said die, and means to move said carrier to the die and thence move said unit further towards said work support, thereby to ornament the work. 100
6. A machine for ornamenting shoe parts comprising a work support, a die unit including a die carrier and a die, means attaching said die to the carrier for yielding movement relative thereto, means to move said die relative to its carrier and in proximity to the work support, whereby work on the latter support may be aligned relative to said die, and means to move said carrier to the die and thence move said unit further towards said work support, thereby to ornament the work. 110
7. A machine for ornamenting shoe parts comprising a work support, a member movable toward and from said work support, a die, means attaching said die to said member for movement therewith, including a plate interposed between the die and member and connected to the die and resilient means connecting said plate to said member, means to move said die yieldingly relative to said member in proximity to said support, whereby the work may be aligned on said support relative to said die, and means to move said member and die as a unit, toward said support thereby to ornament the work. 120
8. A machine for ornamenting shoe parts comprising a work support, a member movable toward and from said work support, a die, means mounting said die upon said member, including a pair of plates interposed between the die and member, one of said plates being connected to the die and the other of said plates being connected to the member, and yieldable means connecting said plates to each other, means to move said die relative to said member in proximity to said support whereby the work may be aligned on said support relative to said die, and means to move said member and die as a unit, toward said support thereby to ornament the work. 130
9. A machine for ornamenting shoe parts comprising a work support, a member movable toward and from said work support, a die, means mounting said die upon said member, including a pair of plates interposed between the die and member, one of said plates being connected to the die and the other of said plates being connected to the member, and yieldable means connecting said plates to each other, means to move said member and die as a unit, toward said support thereby to ornament the work. 140
10. A machine for ornamenting shoe parts comprising a work support, a member movable toward and from said work support, a die, means mounting said die upon said member, including a pair of plates interposed between the die and the member, one of said plates being connected to the die and the other of said plates being connected to the member and yieldable means connecting said plates to each other, means to move said die relative to said member in proximity to said support, power means to move said member and die as a unit, toward said support, thereby to ornament the work, and control means for said power means positioned for actuation by said die moving means, after the die reaches a predetermined position. 150
11. A machine for ornamenting shoe parts comprising a work support, a member movable toward and from said work support, a die, means mounting said die upon said member, including a plate interposed between the die and the member, and connected to the die, yieldable means connecting the plate to said member, and operator controlled means connected to said plate and effective to separate the plate from the member, whereby the work may be aligned on the support relative to said die, and means to move said member and die as a unit toward said support thereby to ornament the work. 160
12. A machine for ornamenting shoe parts comprising a work support, a member movable toward and from said work support, a die, means mounting said die upon said member, including a pair of plates interposed between the die and the member, one of said plates being connected to the die and the other of said plates being connected to the member, and yieldable means connecting said plates to each other, operator controlled means connected to one of said plates and effective to separate said plates whereby the work may be aligned on said support relative to said die, and means to actuate said member and die as a unit whereby to ornament the work. 170
13. A machine for ornamenting shoe parts comprising a work support, a member movable toward and from said work support, a die, means mounting said die upon said member, including a pair of plates interposed between the die and the member, one of said plates being connected to the die and the other of said plates being connected to the member, and yieldable means connecting said plates to each other, operator controlled means connected to one of said plates and effective to separate said plates whereby the work may be aligned on said support relative to said die, and means independent of said separating means for actuating said member and die as a unit toward said support thereby to ornament the work. 180
14. A machine for ornamenting shoe parts comprising a work support, a member movable toward and from said work support, a die, means mounting said die upon said member, including a pair of plates interposed between the die and the member, and yieldable means connecting said plates to each other, operator controlled means connected to one of said plates and effective to separate said plates whereby the work may be aligned on said support relative to said die, and means to move said member and die as a unit, toward said support, thereby to ornament the work. 190

- member, one of said plates being connected to the die and the other of said plates being connected to the member, and yieldable means connecting said plates to each other, operator controlled means connected to one of said plates and effective to separate said plates whereby the work may be aligned on said support relative to said die, means for actuating said member and die as a unit toward said support thereby to ornament the work, and means to lock said actuating means against operation until said plates reach a predetermined separated position.
15. In an ornamenting machine, a resilient die holder for mounting a die in the machine, comprising a pair of plates having a yieldable connection therebetween, means on one of said plates for attaching the die holder to the machine, and means on the other of said plates for attaching a die to the holder.
20. 16. In an ornamenting machine, a resilient die holder for mounting a die in the machine, comprising a pair of plates having a yieldable connection therebetween, means on one of said plates for attaching the die holder to the machine, and means on the other of said plates for attaching a die to the holder, and means to separate the plates thereby to position the die adjacent the work.
25. 17. In an ornamenting machine, a resilient die holder for mounting a die in the machine, comprising a pair of plates having a yieldable connection therebetween, means on one of said plates for attaching the die holder to the machine, means on the other of said plates for attaching a die to the holder, means to separate the plates thereby to position the die adjacent the work, and means for moving said die holder and die into ornamenting relation to the work.
30. 18. A machine for ornamenting shoe parts comprising a work support, a die support, and a die unit on said latter support, having a plurality of cutting edges, certain of said edges being rigidly mounted in said unit and others of said edges being resiliently mounted in advance of said first edges, means to move said unit relative to its support in proximity to the work support with said advanced edges engaging the work on said support whereby the work may be aligned relative to the unit, and means to provide relative movement between said work support and die support thereby to ornament the work.
35. 19. A machine for ornamenting shoe parts comprising a work support, a die support, and a die unit including a plurality of cutting edges, certain of said edges being rigidly mounted in said unit and others of said edges being resiliently mounted in advance of said first edges, means resiliently mounting said unit on the die support, means including said resilient means to move said unit relative to its support in proximity to the work support with said advanced edges engaging the work on said support, whereby the work may be aligned relative to the die, and means to provide relative movement between said work support and die support, thereby to ornament the work.
40. 20. A machine for ornamenting shoe parts comprising a work support, a member movable toward and from said work support, a die unit having a plurality of cutting edges, certain of said edges being rigidly mounted in said unit and others of said edges being resiliently mounted in advance of said first edges, means mounting said unit upon said member, including a plate interposed between the unit and the member and connected to the unit, and resilient means connect-
- ing said plate to said member, means to move said unit relative to said member in proximity to said support with said advanced edges engaging the work on said support whereby the work may be aligned relative to the die, and means to move said member and die as a unit toward said support thereby to ornament the work.
45. 21. A machine for ornamenting shoe parts comprising a work support, a member movable toward and from said work support, a die unit having a plurality of cutting edges, certain of said edges being rigidly mounted in said unit and others of said edges being resiliently mounted in advance of said first edges, means mounting said unit upon said member including a pair of plates interposed between the unit and the member, one of said plates being connected to the die and the other of said plates being connected to the member and yieldable means connecting said plates to each other, means to move said unit relative to said member in proximity to said support with said advanced edges engaging the work on said support whereby the work may be aligned relative to the die, and means to move said member and die as a unit toward said support thereby to ornament the work.
50. 22. A die for forming ornamental cutouts in a work piece comprising a die block, a cutting member rigid with said block, and a cutting member resiliently mounted upon said block.
55. 23. A die for forming ornamental cutouts in a work piece comprising a die block, a cutting member rigid with said block and a cutting member resiliently mounted upon said block, said resiliently mounted cutter being normally positioned with its cutting edges in advance of the cutting edges of the fixed cutter.
60. 24. A die for forming ornamental cutouts in a work piece comprising a die block, a rigid projection thereon and a hollow cutting member rigid with said projection, said projection having a passage therethrough in communication with the interior of said cutter to permit the passage of chips therethrough, and a cutting member resiliently mounted upon said block, having its cutting edges normally spaced in advance of the cutting edges of said fixed cutter.
65. 25. A device of the character described comprising a die holder having therein a socket, a movable member extending therewith, and normally, partially, obstructing said socket, said member having a cutout portion, a die, a base therefor, means mounting said die on one side of said base, in spaced relation to form therewith, a chamber for the reception of chips, an abutment projecting from the other side of said base and adapted to extend into said socket, said abutment having a notch to receive said member, means to move said member to register the cutout portion thereof with said socket, whereby the abutment may be inserted, and to thereafter move said member to remove the cutout portion and engage said member with the notch of the abutment.
70. 26. A device of the character described comprising a die holder having therein a socket, a rotary member extending transversely of and normally, partially obstructing said socket, said member having a cutout portion, a die, a base therefor, means mounting said die on one side of said base, in spaced relation to form there- with, a chamber for the reception of chips, an abutment projecting from the other side of said base and adapted to extend into said socket, said abutment having a notch of a size and shape corresponding to the size and shape of said rotary

member, means to rotate said member to register the cutout portion thereof with said socket whereby the abutment may be inserted, and to thereafter rotate said member to remove the cutout portion and engage said member with the notch of the abutment.

27. A device of the character described comprising a die holder having therein a socket, a locking member having a portion movable into and out of said socket, a die, a base therefor, means mounting said die on one side of said base, in spaced relation to form therewith, a chamber for the reception of chips, a notched abutment projecting from the other side of said base and adapted to extend into said socket for engagement with said locking member when said portion thereof is positioned in the socket, and means to move said portion relative to the socket.

28. A device of the character described comprising a die holder having therein a socket, a locking member having a portion movable into and out of said socket, a die, a base therefor, means mounting said die on one side of said base, in spaced relation to form therewith, a chamber for the reception of chips, a notched abutment projecting from the other side of said base and adapted to extend into said socket for engagement with said locking member when said portion thereof is positioned in the socket, and means to move said portion relative to the socket, said base and holder also having a relatively engageable pin and socket to accurately locate the die on the holder and, by cooperation with the said member and first named socket, fix said die in position on the holder.

29. A device of the character described comprising a die support, a locking means thereon, a die, a base therefor, means mounting said die on one side of said base, in spaced relation to form therewith, a chamber for the reception of chips, an abutment projecting from the other side of said base, said abutment having a notch engageable and cooperative with said means to secure the die to said support, said base and support having a relatively engageable pin and socket to accurately locate the die on the support and retain same fixedly in supported position.

30. A machine for ornamenting shoe parts comprising a work support, a die unit including a die carrier and die mounted on said carrier, means to move said die relative to its carrier and through a plane normal to the work support whereby work thereon may be aligned relative to the die, means to adjust the position of said work support relative to said die unit, and means to provide relative movement between said work support and die unit through a plane perpendicular to the work support, thereby to ornament the work.

31. A machine for ornamenting shoe parts, comprising a work support, a die unit including a die carrier and a die attached to said carrier, means to move said die relative to its carrier and through a plane normal to the work support, whereby work thereon may be aligned relative to said die, means to adjust the position of said work support relative to said die unit, and means to move said carrier to the die and thereafter move said unit further toward said work support thereby to ornament the work.

32. A machine for ornamenting shoe parts comprising a work support, a die unit including a die holder and die mounted thereon, means to move said die relative to its holder and through a plane normal to the work support whereby a work piece may be aligned relative to the die, means to ad-

just the position of said work support, through a substantially horizontal plane, relative to said die unit, and means to provide relative movement between said work support and die unit through a plane perpendicular to the work support thereby to ornament the work.

33. A machine for ornamenting shoe parts comprising a work support, a die unit including a die holder and a die attached thereto, means to move said die relative to its holder and through a plane normal to the work support, whereby a work piece may be aligned relative to said die, means to adjust the position of said work support through a substantially horizontal plane, relative to said die unit, and means to move said holder to the die, and thereafter move said unit further toward said work support thereby to ornament the work.

34. A machine for ornamenting shoe parts comprising a work support, a die unit including a die holder, and die mounted thereon, means to move said die relative to its holder and through a plane normal to the work support, whereby a work piece may be aligned relative to the die, means to adjust the position of said work support relative to said die unit, through a plane substantially parallel to the plane of the cutting edges of said die, and means to provide relative movement between said work support and die unit through a plane perpendicular to the work support thereby to ornament the work.

35. A machine for ornamenting shoe parts comprising a work support, a die unit including a die holder and a die attached thereto, means to move said die relative to its holder and through a plane normal to the work support whereby a work piece may be aligned relative to said die, means to adjust the position of said work support relative to said die unit, through a plane substantially parallel to the plane of the cutting edges of said die, and means to move said holder to the die, and thereafter move said unit further toward said work support, thereby to ornament the work.

36. A machine for ornamenting shoe parts comprising a work support, a die unit including a die holder, and die mounted thereon, means to move said die relative to its holder and through a plane normal to the work support, whereby a work piece may be aligned relative to the die, means to adjust the position of said work support relative to said die unit, through a plane substantially parallel to the plane of the cutting edges of said die, comprising a movable member connected to said work support, a guide for said member, and means connected to said member for moving the member and work support as a unit, and means to provide relative movement between said work support and die unit through a plane perpendicular to the work support thereby to ornament the work.

37. A machine for ornamenting shoe parts comprising a work support, a die unit including a die holder and die attached thereto, means to move said die relative to its holder and through a plane normal to the work support whereby a work piece may be aligned relative to said die, means to adjust the position of said work support relative to said die unit, through a plane substantially parallel to the plane of the cutting edges of said die, comprising a movable member connected to said work support, a guide for said member and means connected to said member for moving the member and work support as a unit, and means to move said holder to the die, and there-

after move said unit further toward said work support thereby to ornament the work.

38. A machine for ornamenting shoe parts comprising a frame, a fixed guide therein, a work support having an upper surface positioned in a plane normal to said guide and in substantial alignment therewith, a member mounted for reciprocating movement in said guide, a die attached to said member for movement therewith means to move said die independently of said member through a plane normal to the work support, whereby a work piece may be aligned relative to said die, and means to move said member and die through the same plane to ornament the work.

15 39. A machine for ornamenting shoe parts comprising a frame, a fixed guide therein, a work support having an upper surface positioned in a plane normal to said guide and in substantial alignment therewith, a member mounted for reciprocating movement in said guide, a die attached to said member for movement therewith, manual means to move said die independently of said member through a plane normal to the work support, whereby a work piece may be aligned relative to said die, and power driven means to move said member and die through the same plane to ornament the work.

20 40. A machine for ornamenting shoe parts comprising a work support, a plunger reciprocable toward and from said work support, a die unit including a die holder attached to said plunger, and a die carried by said holder, means to move said die relative to its holder and through a plane normal to the work support, whereby a work piece may be aligned relative to said die, and means to provide relative movement between said work support and die unit through a plane normal to the work support, thereby to ornament the work.

25 41. A machine for ornamenting shoe parts comprising a frame, a fixed guide therein, a work support having an upper surface positioned in a plane normal to said guide and in substantial alignment therewith, a member mounted for reciprocating movement in said guide, a die attached to said member for movement therewith, means to move said die through a plane normal to the work support, whereby a work piece may be aligned relative to said die, and means to move said die further through the same plane to ornament the work, and resilient means effective to normally maintain said die in engagement with said member.

30 42. A machine for ornamenting shoe parts comprising a frame, a fixed guide therein, a work supporting member movably mounted on said frame and having an upper surface positioned in a plane normal to said guide and in substantial alignment therewith, means forming part of said machine for positively moving said member and surface thereby to adjust the position of the work supporting member through a substantially horizontal plane, a member mounted for reciprocating movement in said guide, a die attached to said member for movement therewith, means to move said die through a plane normal to said support, whereby a work piece may be aligned relative to said die, and means to move said die further through the same plane to ornament the work.

35 43. A machine for ornamenting shoe parts comprising a frame, a fixed guide therein, a work supporting member movably mounted on said frame and having an upper surface positioned in a plane normal to said guide and in substan-

tial alignment therewith, means forming part of said machine for positively moving said member thereby to adjust the position of the supporting member through a substantially horizontal plane, a member mounted for reciprocating movement in said guide, a die attached to said member for movement therewith, manual means to move said die through a plane normal to said support, whereby a work piece may be aligned relative to said die, and power driven means to move said die further through the same plane to ornament the work.

44. A machine for ornamenting shoe parts comprising a frame, a fixed guide therein, a work supporting member movably mounted on said frame and having an upper surface positioned in a plane normal to said guide and in substantial alignment therewith, means forming part of said machine for positively moving said member thereby to adjust the position of the supporting member through a substantially horizontal plane, a member mounted for reciprocating movement in said guide, a die attached to said member for movement therewith, means to move said die through a plane normal to said support, whereby a work piece may be aligned relative to said die, and means to move said die further through the same plane to ornament the work.

45. A machine for ornamenting shoe parts comprising a frame, a fixed guide therein, a work supporting member movably mounted on said frame and having an upper surface positioned in a plane normal to said guide and in substantial alignment therewith, means forming part of said machine for positively moving said member thereby to adjust the position of the supporting member through a substantially horizontal plane, a member mounted for reciprocating movement in said guide, a die attached to said member for movement therewith, manual means to move said die through a plane normal to said support, whereby a work piece may be aligned relative to said die, and power driven means to move said die further through the same plane to ornament the work.

46. A machine for ornamenting shoe parts comprising a frame, a fixed guide therein, a work supporting member movably mounted on said frame and having an upper surface positioned in a plane normal to said guide and in substantial alignment therewith, means forming part of said machine for positively moving said member thereby to adjust the position of the supporting member through a substantially horizontal plane, a plunger mounted for reciprocating movement in said guide, a die interposed between said member and said plunger, means mounting said die for movement solely through the plane of movement of said plunger, yieldable means normally holding said die mounting means and plunger closely together, means to move the die through its operating plane toward said member, whereby a work piece may be aligned relative to said die, and means to move said die further through the same plane to ornament the work.

47. A machine for ornamenting shoe parts comprising a frame, a fixed guide therein, a work supporting member movably mounted on said frame and having an upper surface positioned in a plane normal to said guide and in substantial alignment therewith, means forming part of said machine for positively moving said member thereby to adjust the position of the supporting member through a substantially horizontal plane, a plunger mounted for reciprocating movement

in said guide, a die interposed between said member and said plunger, means mounting said die for movement solely through the plane of movement of said plunger, yieldable means normally holding said die mounting means and plunger closely together, manual means to move the die through its operating plane toward said member, whereby a work piece may be aligned relative to said die, and power driven means to move said 10 plunger and die through the same plane to ornament the work.

48. A machine for ornamenting shoe parts, comprising a work supporting member movably mounted on said machine, and having a flat upper 15 surface, a die holder, a die operatively engaged therewith, means to move said die through a plane normal to said support, whereby a work piece may be aligned relative to said die, means to adjust the position of said member relative 20 to said die, and through a plane substantially parallel to the plane of the cutting edges of said die, comprising a movable member connected to

said supporting member, a guide for said movable member, and means connected to said movable member for positively moving both members as a unit, and means to move said die further toward said surface thereby to ornament the 83 work.

49. A machine for ornamenting shoe parts, comprising a work supporting member movably mounted on said machine, and having a flat upper 86 surface, a die holder, a die operatively mounted thereon, means to move said die through a plane normal to said support, whereby a work piece may be aligned relative to said die, means forming part of said machine for positively moving said member thereby to adjust the position of the 93 member through a substantially horizontal plane relative to said die unit, and means to provide relative movement between said support and die through a plane normal to said support, thereby to ornament the work.
